TENNIS BALL RETRIEVER

Dalny Travaglio, Kensington, Calif., assignor to
Madewell Products, Inc., Oakland, Calif.

Filed Oct. 23, 1974, Ser. No. 517,086

Term of patent 14 years

Int. Cl. D21—02

U.S. Cl. D34—5 CB

FIG.—1

FIG.—2

FIG.—3

FIG.—4

FIG.—5

FIG. 1 is a front elevational view of a tennis ball retriever showing my new design;

FIG. 2 is a side elevational view thereof, the opposite side being a mirror image thereof;

FIG. 3 is a rear elevational view thereof;

FIG. 4 is a top plan view thereof; and

FIG. 5 is a bottom plan view thereof.

I claim:

The ornamental design for a tennis ball retriever, as shown and described.
